United States Patent Office

Des. 198,227
Patented May 19, 1964

198,227

SOCK

Paul E. Johnson, Jr., P.O. Box 324, Marietta, Ga.

Filed Dec. 16, 1963, Ser. No. 77,798

Term of patent 14 years

(Cl. D47—7)

The single figure illustrates one side of a sock embodying my design with the other side of the sock being identical in appearance.

I claim:

The ornamental design for a sock, as shown and described.
